Fig 6.

Fig. 7.

Fig. 9.

The image contains two technical drawings. The left drawing, labeled 'Fig. 8', shows a side view of a mechanical assembly. It features a base plate with a central screw and a slot. A cylindrical component with a ribbed base is inserted into the slot, secured by a lock washer (93) and a lock nut (90). A small cylindrical part (94) is attached to the base plate. The right drawing, labeled 'Fig. 9', shows a top-down view of a track system. A horizontal rail (89) is supported by a vertical post (88). A small cylindrical part (87) is shown near the rail.

UNITED STATES PATENT OFFICE

2,591,974

TRAVERSING HOIST

Charles R. Smith, Chicago, Ill.

Application August 20, 1948, Serial No. 45,345

4 Claims. (Cl. 212—61)

1

This invention relates to traversing hoists of the type particularly adapted for roofers' and builders' use but capable of a variety of additional uses. This invention may be considered a further development of the hoists forming the subjects of my Patents No. 2,305,202, granted December 15, 1942; and No. 2,379,599 granted July 3, 1945.

Among objects of the present invention is the provision of cable guide means from the cable drum to the load to insure against the fouling of the cable with the hoist structure in hoist operation and to permit of the even winding of the cable upon the drum. A further object is to provide a traversing hoist having a power transmission including novel and simple means for materially increasing lift power over structures of conventional type familiar to me; and a hoist wherein the power in use automatically releases the brake during the lift of the load and with the power off the weight of the load automatically sets the brake thus providing safety in operation.

A further object is to provide a hoist with single control means for starting the motor and engaging the transmission clutch simultaneously and thereafter accelerating the motor and, conversely, that may be employed to decelerate motor speed and thereafter disengage the transmission clutch to provide a smooth stop, this operation being accomplished by the operator with the use of one hand only. A still further object is to provide a traversing hoist having a boom capable of easy swing through an arc of 190 degrees or more thus affording greater accessibility to all parts of the roof. Another object is to provide a traversing hoist having a motor that is readily adjustable to permit taking up slack in the operating gear, changing the chain and sprocket drive to the winch, and one wherein the motor is so supported as to be readily removed for repair, cleaning or renewal of parts as may be desired. A further object is to provide a traversing hoist of compact assembly, of durable construction, that is inexpensive in operation, of well balanced setup, that may be readily partly dismantled to facilitate transport, storage etc. and wherein all parts are accessible for inspection, adjustment and the like.

Other objects, novel features and advantages of arrangement, construction and design comprehended by the invention are hereinafter more fully pointed out or made apparent from the following description of a preferred embodiment as illustrated in the accompanying drawings where-

2

in like reference characters denote corresponding parts throughout.

In the drawings:

Fig. 1 is a side view of the instant hoist.

Fig. 2 is an enlarged detail view of the hoist showing the cable guide in plan.

Fig. 3 is a cross sectional view through Fig. 1 on the line 3—3, enlarged, an altered position of adjustable parts being denoted in dotted lines.

Fig. 4 is a vertical cross sectional view through Fig. 3 on the line 4—4.

Fig. 5 is a horizontal cross sectional view through Fig. 1 on the line 5—5.

Fig. 6 is an enlarged fragmentary plan view of Fig. 1, an interchangeable handle being denoted in dotted lines.

Fig. 7 is a view of Fig. 6 in side elevation.

Fig. 8 is a view in elevational perspective of certain control mechanism, and,

Fig. 9 is a view in elevation and partly in section of the brake drum with brake band and brake band lever.

The reference numeral 10 denotes the jack substantially triangular in shape but with the base 11 extending well beyond the sides 12, 13 and disposed preferably upon a 2 x 8 plank or the like, to which the base is secured by straps 15 to avoid otherwise possible lateral tilt in operation. Each side is provided with steel rod reinforcement 16 or the like for maximum strength. At

approximately the longitudinal center of the jack and extending transversely and slightly forwardly thereof is the tubular brace 18 that supports the cam socket 19 forming a bearing for the lower end of the lower side 20 of the swinging boom 21, the upper side 22 being received in a similar socket 23 in the apex of the jack, the cam sockets 19, 23 disposed in line with each other immediately forward but contiguous to the plane of the jack,

said boom sides being connected by reinforcement structure 24 and at its forward end provided with the sheave 25. The boom is here so supported as to have a swing through an arc of 190 degrees or more and is disposed at an obtuse angle to the jack.

Pivotedly secured to a bracket 26 carried by the socket 19 is the connecting bar 27 that is likewise secured to the collar 28 carried by truss bar 29 provided with reinforcement structure 30, said truss bar at its lower end provided with the counterbalance weight rest 31 and at its upper end pivotally secured to the bracket 32 carried by the jack. Supported upon the structure 30 is the frame 33 supporting bearings 34 for the shaft 35 free upon which is the brake drum 36 engaged

by brake band 37 one end of which is secured to said frame 33 and the opposite end to the control lever 38 fulcrumed to the standard 39 carried by said frame, one end of said lever engaged by the brake cord 40 connected to the jack. Also free upon said shaft 35 is the cable drum 41 having wound thereupon the cable 42 that passes between guide rollers 43, two in number, carried by said frame and therebeyond between the juxtaposed cable guide sheaves 44, 44 to and over the sheave 25 at the forward end of the boom and provided at its end with the hook 45.

Referring again to the juxtaposed cable sheaves 44, 44 same are pivotally mounted to the spaced parallel studs 46, 46 connected by yoke 46a and carried by the bracket 47 pivotally connected by the pin 48 to the block 49 that freely but snugly receives the upper boom side 22 formed with three spaced perforations 50 to selectively receive the pin 51 to releasably secure said block in adjusted position upon said side, the block 49 being formed with the recess 52 to afford clearance for a reinforcement 24 in the forward position of block 49. Also secured to the block 49 and extending laterally from each side thereof is an arcuate stop 53 for engagement with the bracket 47 as same may swing from its full line position, Fig. 3, to either dotted line position.

The several perforations 50 in boom side 22 are located forwardly of a straight line 50a passing axially of the down-turned ends of the boom sides 20, 22 and the point of engagement of the cable 42 with the sheaves 44 so that the weight of the load upon hook 45 will assist in a lateral movement of the boom when such movement may be desired and initiated. Free upon the shaft 35 is a cog wheel 54, connected to said cable drum 41 and brake drum 36, in mesh with a pinion 55 keyed upon transmission shaft 56 carried by the frame, a collar 57 also keyed to shaft 56 is operable by lever 58 for movement of said pinion into and out of engagement with cog wheel 54, said lever fulcrumed to a brace 59 carried by the frame 33, said brace having secured thereto a stand 59a engaging one end of the contractile coil spring 60 connected to the said lever 38 yieldingly retaining same in position to very slightly and yieldingly engage the brake band with the drum. The brake cord 40 is adjustably secured to the jack so that the pull of the spring 60 may be set as desired and the wear of the band rendered negligible.

The brake is a one-way acting brake and when the motor drives the cable drum in a direction to take in the cable and hoist the load the action of the brake drum is to push the brake band to a lesser gripping position and hence the band does not hold the drum against such winding or hoisting rotation. During the lowering operation the lever 58 is employed to move the collar 57 to disengage the pinion 55 from the cog wheel 54 thus freeing the drum 41 from its driving connection whereupon the drum would be under control of the brake cord 40 for rapid, yet controlled, lowering of the load. Secured to one end of the transmission shaft 56 is the cone 61 provided with the sprocket wheels 62, 63, 64 of different sizes for connection selectively by the chain 65 to the corresponding sprocket wheels 66, 67, 68 fast to the engine shaft 69 of the engine 70 provided with the handle 71, said engine shaft adapted for engagement at one end by the crank 72 for cranking the motor when desired, said crank also adapted for engagement in like manner with the shaft 56. The teeth 75

of the sprocket wheels 66, 67, 68 are fewer in number than the teeth of the sprocket wheels 62, 63, 64 of corresponding size thus slowing down the speed of shaft 56 relative to shaft 69 and increasing the lifting power. The motor assembly is secured to the tilting table 73 which is hinge-connected by the angular pin 74 to the frame 33, the table being connected at its opposite end by the bracket 75 and pivot pin 76 to the plunger 77 removably received in the cylindrical sleeve 78 and provided with a collar 79 adjustably secured thereto by set screw 80, said collar serving as a stop for arresting the movement of the plunger into the sleeve, said plunger also adapted for engagement by the angular lock screw 81 received in the threaded nose 82 of said sleeve, said sleeve supported by the bracket 84 pivotally carried by the reinforcing structure 30. By loosening the screw 81 the table 73 with motor may be tilted upwardly and forwardly as denoted in dotted lines, Fig. 7, to slack the chain 65 to permit shifting the chain from one set of oppositely disposed sprocket wheels to another to vary the speed or to compensate for wear of the chain when necessary. Secured to one end of shaft 56 by the clutch collar 85 is one end of the throttle control lever 86 having the handle 87, said lever connected by link 88 and pins 89 to the bell crank 90 mounted to the casting 91 carried by supporting arm 92 connected to the frame, said bell crank connected by the flexible shaft 93 to the lever of the motor carburetor 94. By moving the lever 86 in one direction a certain distance the motor is started through shaft 93 and the clutch thrown in thus operatively connecting the engine shaft 69 and shaft 56 and a further lever movement in the same direction will speed up the motor.

What is claimed is:

1. In a traversing hoist, a mast having a stance at an angle to the perpendicular, a support for said mast including a truss bar and a bar connecting said mast and truss bar, a boom mounted to said mast to swing thereabout, sheave mechanism at one end of said boom, a winch carried by said support, juxtaposed sheaves carried by said boom adjacent said mast, and a cable about said winch passing between said sheaves and over said sheave mechanism.

2. In a traversing hoist, a mast having a stance at an angle to the perpendicular, a support for said mast including a truss bar and a bar connecting said mast and truss bar, cam sockets carried by said mast disposed in a straight line parallel to and forwardly of the plane of said mast, a boom journaled in said sockets, a sheave at one end of said boom, juxtaposed sheaves carried by said boom adjacent said mast, stops for said sheaves carried by one of said cam sockets, a winch carried by said support and a cable about said winch passing between said juxtaposed sheaves and over said first named sheave.

3. In a traversing hoist, a mast, a truss bar supporting said mast, a swinging plurally perforated boom mounted to said mast, a sheave at one end of said boom, guide sheaves carried by said boom adjacent said mast, guide sheave mounting means carried by said boom, said means including a pin engageable in selected boom perforations to effect guide sleeve adjustment longitudinally of said boom, a winch carried by said truss bar, and a cable about said winch passing between said guide sheaves and over said first named sheave.

4. In a traversing hoist, a mast having a stance

at an angle to the perpendicular, a support for said mast including a truss bar and a bar connecting said mast and truss bar, cam sockets carried by said mast disposed in a straight line parallel to and forwardly of the plane of said mast, a swinging boom having downturned rear terminals journaled in said sockets, a sheave terminally carried by said boom, juxtaposed guide sheaves adjustably carried by said boom adjacent said mast, a winch carried by said support, and a cable about said winch passing between said sheaves and over said first named sheave, the point of contact of said cable with said juxtaposed sheaves being in said straight line in one position of said sheaves.
